CLAIM

The ornamental design for a telephone set, substantially as shown and described.

DESCRIPTION

FIG. 1 is a front elevational view of a telephone set showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front, bottom and left side perspective view of the handset thereof, and a front, top and right side perspective view of the stand spaced apart from the handset.

The coiled cord is not shown in FIGS. 1-6 for convenience of illustration and clarity of representation.
